UNITED STATES PATENT OFFICE.

MARK W. DEWEY, OF SYRACUSE, NEW YORK.

DESIGN FOR AN ELECTRIC-HEATER CASE.

SPECIFICATION forming part of Design No. 23,528, dated July 31, 1891.

Application filed June 15, 1894. Serial No. 514,701. Term of patent 14 years.

To all whom it may concern:

Be it known that I, MARK W. DEWEY, a citizen of the United States, residing at Syracuse, in the county of Onondaga and State of New York, have invented and produced a new and useful design for an Electric-Heater Case, of which the following is a specification, reference being had to the accompanying drawings, showing a part thereof.

10 Figure 1 is a side elevation in perspective of an electric heater case showing my design, and Fig. 2 is a vertical cross sectional view of the same.

15 The leading feature of my design consists in a rectangular side joined to and integral with the entire top, bottom and ends, the top and bottom of the case, or the upper and lower part thereof, being provided with openings.

A is the case formed of metal and rectangular in shape.

²⁰
a, a are rows of openings in the top and bottom and extending upon and through the side of the case.

This construction presents to the eye an attractive and pleasing effect, and possesses ²⁵ utility.

What I claim is—

The design for an electric heater casing, substantially as shown and described.

MARK W. DEWEY.
